UNITED STATES PATENT OFFICE.

MICHAEL A. DROITCOUR, OF DELPHOS, OHIO.

PRINTING-PRESS.

1,356,051.

Specification of Letters Patent. Patented Oct. 19, 1920.

Application filed April 11, 1917, Serial No. 161,338. Renewed October 23, 1919. Serial No. 332,852.

To all whom it may concern:

Be it known that I, MICHAEL A. DROITCOUR, a citizen of the United States, and a resident of Delphos, in the county of Allen, 5 and State of Ohio, have invented a certain new and useful Printing-Press; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 This invention relates to apparatus in which a reciprocally movable bed or member is employed, and particularly to improved means for reciprocating the type-beds of printing presses of the flat-bed and cylindri- 20 cal type.

The primary object of my invention is to provide novel means for driving a printing press bed and reversing its movements at the end of each stroke, the reversing being ac- 25 complished in an efficient and rapid manner without jar or shock, thus enabling the press to be run at a very high speed without liability of racking the same.

Further objects and advantages of the in- 30 vention will be apparent from the following detailed description thereof.

While the invention, in its broader aspect, is capable of embodiment in numerous forms, a preferred embodiment thereof is 35 illustrated in the accompanying drawings in which,—

Figure 1 is a side elevation of a press embodying my invention, with parts broken away. Figs. 2 and 3 are different fragmentary detailed views of the impression control means, with parts in section on the line 3—3 in Fig. 4. Fig. 4 is a top plan view of the press, with the cylinder and bed removed, with a part broken away, and with a portion 40 of the vibrating inking rolls in position. Fig. 5 is a section on the line 5—5 in Fig. 1. Fig. 6 is a section on the line 6—6 in Fig. 5, with parts removed and parts broken away. Fig. 7 is an enlarged perspective view of a 45 part of the impression control means. Figs. 8 and 9 are enlarged sections on the line 8—8 in Fig. 5. Fig. 10 is a fragmentary perspective view of one side portion of the press, with parts removed. Fig. 11 is a 50 fragmentary perspective view of one of the slide frames, with a portion of the rollers

removed. Fig. 12 is a side elevation of the rotary reciprocatory bed driving shaft, with the parts carried thereby in section. Fig. 13 is an enlarged fragmentary perspective 60 view of a portion of the bed reversing mechanism. Figs. 14, 15, 16 and 17 are conventional side views of the bed and cylinder driving mechanism at different points in a cycle of operations with parts broken away, 65 and Fig. 18 is a section on the line 18—18 in Fig. 1.

Referring to the drawings, 1 designates the press frame, of any suitable construction, and 2 the customary bed, which is 70 mounted for reciprocatory movements under a continuously driven impression cylinder 3, as is well understood in the art.

The main drive shaft 4 (Figs. 1 and 4) of the press is mounted transversely in the 75 frame 1 below the bed 2 and fixedly carries a fly-wheel 5, a broad pinion 6, and a narrow pinion 7 without one side of the frame, the pinions 6 and 7 being spaced apart to permit the positioning of a gear therebetween. The pinion 6 meshes with and drives a pinion 8, which is loosely mounted for both rotary and axial sliding movements on a subjacent stub-shaft 9 (Fig. 18). A pinion 10 which is slightly smaller than the pinion 85 8, is fixed to said pinion at its inner side to have rotation and axial movements therewith. A broad pinion 11, which is the same size as the pinion 10, is mounted on the shaft 9 at the inner side of the pinion 10 for free 90 rotary and axial movements. A shipper yoke 12 embraces the set of gears 8, 10 and 11, and is operable, as hereinafter described, to control the axial shifting movements thereof.

A shaft 13 (Figs. 4, 5, 6 and 12) is journaled transversely in the frame 1 at one side of the drive shaft 4 and substantially central of the reciprocatory movements of the bed 2. A pair of gears 14 are keyed to the shaft 13 and are in constant mesh with respective racks 15 (Fig. 5) on the under side of the bed, longitudinally thereof. The two slide frames 16, which carry rollers 17 between the frame runners 18 and bed 2, are caused to have reciprocatory movements with the bed by reason of gears 19, which are fixed to the shaft 13, meshing with racks 20 on said slide frames.

It will be seen that the bed is driven during the uniform portion of its stroke by the gears 14 meshing with the racks 15 and

these gears and racks are disposed on opposite sides of and equidistant from the central longitudinal line of the bed so that the bed is driven forward or backward without any lateral twisting movement or strain such as are caused when only one gear and rack are used under the bed and such rack is at one side of the longitudinal center of the bed. The pinions 14 remain in mesh with the racks 15 at all times but are only operatively controlling the bed during the uniform portions of its stroke, the bed being reversed at the end of its stroke by the mechanism hereinafter explained. By employing a pair of bed driving racks and pinions at opposite sides of the center of the bed, as described, I am enabled to arrange the reverse racks 34 and reverse lever 33 in the plane of the central line of the bed; and with this construction the bed is always centrally driven, and centrally reversed, or balanced, and has no tendency to twist or become laterally displaced during any portion of its stroke.

Lateral twisting movements of the bed are also caused by the impression of the form being heavy on one side of bed and light on the other, the make-ready of course being sometimes heavier or thicker on one side than on the other which would tend to twist the bed; but, because of the arrangement of two tracks and two gears, the bed has a parallel movement regardless of impression strains and the reversing movements being centralized are not affected by the unequal impression pressures as no printing occurs while the bed is being reversed.

The shaft 13 has the end thereof adjacent to the stub-shaft 9 projected without the frame 1 and carrying a loose gear 21 and a fixed gap-gear 22, said gears being of equal size and disposed in close relation and adapted to simultaneously mesh with the broad pinion 11 on the stub-shaft 9 during a predetermined portion of a cycle of operations. The pinion 11 remains in permanent mesh with the gear 21 and is shiftable into and out of mesh with the gear 22 during the bed reversing periods. The pinion 7 on the drive shaft 4 is also in permanent driving connection with the gear 21, thus causing a continuous driving of said gear at a uniform speed in one direction during a running of the press.

The drive-shaft 4 carries a pinion 23 (Figs. 4 and 5) near the transverse center of the press, which pinion meshes with and drives a crank-gear 24, which is mounted on a shaft 25 that is journaled transversely in one side portion of the frame 1 adjacent to one end thereof. The gear 24 has the crank-pin 26 carrying a block 27 (Fig. 13) mounted for vertical reciprocatory movements in a vertical guide portion of a reversing slide or cross-head 28, which is

mounted at its upper and lower ends on guide rods 29 for reciprocatory movements lengthwise of the frame 1. The slide 28 has a rack-bar 30 projecting therefrom toward the longitudinal center of the frame. A reverse lever 31 (Fig. 5) is mounted loosely on the shaft 13 and has its lower arm provided with a segment 32 in mesh with the reverse rack 30 and has its upper arm provided with a segment 33 for meshing with a short bed-reverse rack 34 at the adjacent end of the bed 2 during the reversing movement of the bed, one of said racks 34 being located at each end of the bed. The arm of the lever 31 which meshes with the reverse rack 30 is longer than the arm of such lever which meshes with the bed reverse rack 34, thus enabling the distance between the center of the crank-pin 26 and its axis of revolution to be greater than would otherwise be the case. The bed reversing action of the reversing mechanism is very much facilitated by providing the crank pin of such mechanism with a longer throw than the radius of the bed rack engaging segment 33, it being found in practice that with this mechanism the speed of running of the press (especially if large) can be very materially increased over the speed at which it could be safely run with a reversing mechanism provided with a crank throw which is equal to the radius of the bed reversing segment 33. In the present press the crank has an 8 inch radius, the reverse rack segment 32 has a 12 inch radius, and the bed-reverse rack segment 33 has a 9 inch radius. The crank-gear 24 is geared to have three revolutions for each cycle of operations of the press or for each single revolution of the impression cylinder, one revolution of the crank gear taking place at each impression and return stroke of the bed and a half revolution of such gear taking place at each reverse stroke.

It will be noted that with my reversing mechanism the movements of the reverse rack 30 are always reverse to the movements of the bed during a reversing period. This is an important feature as a balancing action of the bed is thereby obtained and vibration of the press practically eliminated.

In order to prevent wrenching and binding of the reverse slide 28 on the guide rods 29 when power is applied to said slide at one side or the other of its center, the slide is provided with a vertical shaft 35, which is rotatably mounted therein lengthwise thereof and carries a pinion 36 at each end in mesh with a respective fixed rack-bar 37 on the frame 1. The upright shaft 35 fastened to the slide and having pinions 36 meshing with fixed racks 37, holds the slide 28 parallel or square at all times regardless of where the pressure of the wrist pin or block 27 is exerted along the length of the 130

slide; and the twisting or torsional strains which are ordinarily exerted on the slide by the block 27, especially near the ends of its strokes in the grooves in the slide 28, are 5 overcome and equalized throughout the length of the slide by means of the shaft 35, gears 36 and racks 37, which insure a smooth movement of the bed over centers and during the reverse, which is quite important in 10 effecting fine printing, as otherwise some slight vibration is apt to be started during the reverse by the pressure of the block at the ends of the slot in the slide, which vibration would continue, momentarily at 15 least, and cause inferior printing.

A shaft 38 is journaled in the frame 1 transversely thereof and carries a cam wheel 39, which is provided in one side with a cam-way for receiving a roll 40 that is carried by 20 a rack-bar 41. This rack-bar extends longitudinally of the frame and has one end forked and straddling the shaft 38 (Figs. 1, 4 and 5), whereby such bar is supported at one end by the shaft while the other end 25 of said bar rests on and is guided for movements by a frame bracket 42 and is provided with rack teeth in mesh with a gear segment 43 which is carried for horizontal oscillatory movements by said bracket. The 30 segment 43 also meshes with the inner end of a rack-bar 44 which projects inward from and forms a part of the gear shifting yoke 12 and has its movements in a plane at right angles to the plane of movements of the bar 35 41. It is evident that the bar 41 is periodically moved forward and backward by the cam 39 and that its movements are communicated to the gear shifting frame 12 through the gear segment 43.

40 The journals 45 of the cylinder 3 are carried by bearing blocks 46 (Figs. 8 and 9), which are mounted in vertical guide-ways in the frame 1 for vertical reciprocal movements. The blocks 46 are yield- 45 ingly supported by coiled compression springs 47, which normally act to support the cylinder in raised position with respect to the bed. Each block 46 has a short rock- 50 shaft 48 mounted on the top thereof, being partially seated in a depression provided therefor in the top of the block. The top side of the rockshaft 48 is recessed longitudinally thereof to form a seat for the lower end of an impression knuckle 49, 55 which rests for pivotal rocking movements on said rock-shaft and has its upper end seating against the under side of a thrust block 50 in pivotal engagement therewith (Figs. 7, 8 and 9). When the knuckle 49 60 is in vertical position or in radial relation to the rock-shaft 48, the journal block 46 is lowered against the tension of the springs 47 to effect a lowering of the cylinder to impression position, and when the shaft 48 65 is rocked slightly in one direction or the

other the inner end of the knuckle 49 is swung laterally, thereby shortening the distance between the shaft 48 and thrust-block 50 and permitting a raising of the cylinder from impression position. The 70 shaft 48 and knuckle 49 act in the manner of a toggle. The thrust-block 50 is mounted in a head-piece 51 of the frame and is adjusted by means of a screw 52. The ends of the knuckle 49 are provided with trunnions which project into recesses in the flanges provided at the opposite end portions of the rock shaft, as best shown in Fig. 7.

Each rock shaft 48 has a crank arm 53 80 projecting laterally therefrom and connected by a link 54 to a subjacent rocker arm 55 on the adjacent end of a rock shaft 56, which is journaled in the base portion of the frame 1 transversely thereof (Figs. 1, 2 85 and 3). The shaft 56 is provided at one end thereof without the frame 1 with a loose rocker arm 57, which is upwardly directed and carries at its free end a roller 58, which travels in a cam-groove 59 in the side of a 90 gear wheel 60 that is mounted on the outer adjacent end of the shaft 38. The gear wheel 60 is continuously driven by a pinion 61, that is fixed to the continuously driven loose gear 21, the ratio of the gears being 95 such as to cause the gear 60 to make one revolution to each two revolutions of the cylinder 3, which is driven by the gear 21 through a gear 62 of the same size. The rocker-arm 57 has a finger 63 projecting 100 therefrom transversely of its rocking axis and away from the wheel 60, and this finger has a catch or dog 64 pivotally depending therefrom and provided at its lower end with a notch for receiving a stud 105 65 on a side of the adjacent rocker arm 55. The dog 64 normally engages said stud so that the rocker arms 55 and 57 are locked together for unitary movements in the manner of a bell-crank lever. It is thus evident that during an impression stroke of 110 the bed the cylinder is held in lowered position by reason of the roller 58 traveling in the outer neutral portion of the cam-way 59, as shown in Figs. 1 and 3, and that said 115 roller when traveling in the remaining portion of the cam-way permits the cylinder to move to and remain in impression released position.

An impression trip lever 66 (Figs. 2 and 120 3), is pivoted to the side of the frame 1, at which the catch 64 is disposed, and has a finger 67 pivotally projecting upward from the outer end of its free arm and carrying a roller 68. This roller is yield- 125 ingly held in rolling contact with a cam surface 69 at the upper inner side edge of the catch 64 by a spring 70, and upon a depression of the outer end of the lever 66 the roller 68 is caused to travel up the cam 130

- surface 69 and approach the periphery of the cam-wheel 60, and to stand in position for a cam-block 71 on the peripheral portion of the wheel 60 to strike said roller and 5 communicate a trip movement through it to the catch 64 to throw it outward from engagement with the catch-stud 65. This trip can only take place when the roller 58 is in the inwardly retracted portion of the cam-way 59, as is apparent by reason of the position of the parts in Figs. 2 and 3, and the cam-plate 71 is positioned to effect a tripping of the catch 64 shortly before the entrance of the roller 58 into the outer neutral portion of the cam-way 59. It is evident that when the catch 64 is released from the catch lug 65 the rocker arm 57 is permitted to have free rocking movements relative to the shaft 56 and rocker arm 55.
- 20 The normal inactive position of the roller 68 with the trip lever raised is shown in Figs. 2 and 3, and a depression of the trip lever from this position with the parts in the positions shown in Fig. 2 will cause a 25 sufficient movement of the roller 68 by the cam surface 69 to place said roller in position to be engaged and moved outward by the block 71 a sufficient distance to disengage the catch 64 from the lug 65.
- 30 A cam-wheel 72 is fixed to the shaft 13 adjacent to the end thereof opposed to that carrying the gears 21 and 22, and has a cam-way 73 in one side thereof (Fig. 10) in which a roller at the end of a rocker arm 74 travels.
- 35 Fixed to the shaft 75 with this rocker arm, which shaft is journaled in one side of the frame 1, is a gear segment 76 in mesh with a rack-bar 77, which is mounted for longitudinal movements lengthwise of the frame 40 at one side thereof. The bar 77 is provided on its outer side adjacent to each end with a set of rack teeth in mesh with a respective gear segment 78, each of which is fixed to a vertical rock shaft 79 that is suitably journaled in bearings on the frame side. The upper end of each rock shaft 79 is provided with a yoke or cross-head 80, which at its opposite ends engages the adjacent ends of a pair of vibrating inking rolls 81 to impart 45 opposed longitudinal reciprocatory or vibrating movements to said rolls when the shaft 79 is rocked (Figs. 4 and 10).
- 50 The operation of my press is as follows: The main drive shaft 4 when driven imparts continuous rotation to the loose gear 21 from the drive pinion 7, and imparts continuous rotation to the pinions 8 and 10 from the broad drive pinion 6, which is in mesh with the gear 8. The cylinder 3 is also continuously driven at uniform speed with the gear 21 due to the meshing of said gear with the cylinder gear 62 of like size. The reverse crank gear 24 is driven direct from the drive shaft 4 through the medium of the pinion 65 23, which pinion, in the present instance, has

eight revolutions to each impression or cycle of operations of the press, while the ratio of the pinion 23 and gear 24 is such that said gear has three revolutions to each impression. The cam 39, which controls the shifting of the pinions 8, 10 and 11, is geared to have one revolution to each impression of the press. Starting with the impression stroke of the bed, it will be noted (Fig. 14) that the bed-reverse rack segment 33 is just 70 leaving the short bed-reverse rack at the forward end of the bed and the broad pinion 11 is in position to mesh with both gears 21 and 22, and just entering into mesh with the teeth of the gear 22 at the then leaving end 75 of its gap, so that the two gears 21 and 22 are tied together and caused to rotate in unison and to effect a driving of the bed and cylinder at uniform speeds and in synchronism. When the gears 21 and 22 are 80 thus coupled together the drive of the bed is through the shaft 13, gears 14 and racks 15 on the bed. This relation of the bed and cylinder drive parts is maintained until the bed has moved to near the limit of its impression stroke and the bed reverse segment 33 has moved into mesh with the forward end of the rear reverse rack 34 (Fig. 15). At this point the coupling pinion 11 enters the gap of the gear 22, thus disconnecting 85 the gears 21 and 22. When said gears are thus disconnected the drive of the bed is no longer through the shaft 13, pinions 14 and bed racks 15, as the gear 21, which is now the driven gear, is free to turn loosely on said 90 shaft, but the drive of the bed is through the reversing mechanism and is controlled by the crank gear 24. When the reversing segment 33 takes into the rear reverse rack 34 the crank pin is at the lower end of its 95 throw (Fig. 15) and the slowing down, reversing and speeding up of the bed to running speed is accomplished while the crank pin is moving from the lower to the uppermost limit of its stroke (Fig. 16). During 100 the reversing period the gears 21 and 22 are permitted to have relative rotary movements due to the coupling pinion 11 entering the gap of the gear 22, and said pinion, together with the pinions 8 and 10, are then shifted 105 to the left (Fig. 18) to shift the pinion 11 to the pinion 10 into register with the gear 22. It will be understood that the pinion 10 is driven in a reverse direction to the pinion 11 due to the connection of the 110 former with the drive pinion 6 and that the gear 22, during its idle movement or while disconnected from the gear 21, is driven from the bed in synchronism therewith through the racks 15, gears 14 and shaft 13. 115 It is thus evident that the gear 22, during the rearward or return stroke of the bed 2, is revolving in a reverse direction to that of the gear 21. When the movement of the bed at the end of its impression stroke has been 120

reversed and the segment 33 is about to leave the rear reverse rack 34, the gear 22 has turned in a reverse direction relative to the gear 21 a sufficient distance for the teeth 5 at the then leaving end of the gap to take into the pinion 10, so that the rearward stroke is then imparted to the bed from the main shaft 4 through the pinions 6, 8, 10, gear 22, shaft 13 and pinions and racks 14, 10 15 (Fig. 17). It is evident that when the bed is near the end of its rearward stroke the reverse segment 33 takes into the reverse rack 34 at the forward end of the bed at approximately the time that the pinion 10 enters the gap of the gear 22. During the reversing of the movement of the bed by the reversing segment the gear 22 has its direction of rotation reversed to again move in unison with the gear 21 and the pinions 8, 20 10 and 11 are shifted to the right (Fig. 18) to shift the pinion 10 out of and the coupling pinion 11 into register with the gear 22, so that when the end of the gap in the gear 22 in the reverse rotation thereof is 25 reached the coupling pinion 11 will mesh with the teeth of said gear and cause it to be driven in synchronism with the gear 21. During each impression stroke of the bed the cylinder 3 is lowered to impression position by reason of the roller 58 on the 30 rocker arm 57 (Figs. 2 and 3) then traveling in the outer neutral portion of the cam-way 59, thus causing the rocker arm 57 to effect a depression of the rocker arms 55 through 35 the medium of the catch 64 which is in engagement with the catch lug 65 on one of said arms 55. The depression of the arms 55 communicates a downward rocking movement to the rocker arms 53 (Figs. 1, 40 8, 9 and 10) and a consequent rocking of the shafts 48 to move the knuckles 49 to vertical or cylinder depressing position, as shown in Figs. 1 and 8. After the impression stroke, the roller 58 moves to the radially restricted portion of the cam-way 59 and permits a raising of the cylinder to inoperative position. Should it be desired to prevent an impression taking place at any 45 cycle of operations, the operator depresses the foot pedal 66 from the position shown in Fig. 2, thereby throwing the roller 68 upward into position to be engaged by the cam-plate 71 at a predetermined point in its revolution. The engagement of said roller 50 by the cam-plate causes an outward swinging of the catch 64 from stud engaging position, so that a rocking movement of the rocker arm 57 will not be communicated to the rocker arms 55. The cylinder will 55 continue to miss impressions so long as the foot pedal 66 remains depressed.

It will be seen that the gears 14 and bed racks 15 remain constantly in mesh and perform an important office during the period of 60 reversal of the bed, as they then act to drive

the gear 22 while it is out of mesh with gears 11 or 10; and to slow down this gear 22 with the bed, and reverse its direction of rotation and speed it up, to an equal speed of rotation with the gear 21, and in the 70 proper direction of rotation to be engaged by and meshed with either the gear 11 or the gear 10. Thus the bed will be driven during the uniform portion of its stroke by the gear 22 operating shaft 13 and driving the gears 75 14 meshing the racks 15; and the direction of the rotation of the shaft 13 is reversed, during the reversals of the bed, by reason of the continuous mesh of the gears 14 with the bed racks 15. 80

I wish it understood that my invention is not limited to any specific arrangement, construction or form of the parts, as the present embodiment thereof is merely illustrative of the invention and capable of numerous modifications and changes without departing from the spirit of the claims. 85

Having thus described my invention, what I claim as new and desire to secure by Letters Patent, is— 90

1. In combination, a reciprocating bed having a reverse rack at each end, means for driving said bed and idling with respect thereto at the reversing points in its movements, and a reversing mechanism embodying a revolving crank, a rack reciprocally movable by said crank, and a lever having at one end a segment in mesh with said last rack and at its other end a segment which meshes with one or the other of said bed reverse racks to communicate a reversing movement to the bed at the end of each stroke thereof. 95

2. A combination as called for in claim 1, wherein the arms of said lever and the throw of said crank are each different in length. 100

3. A combination as called for in claim 1, wherein the arm of said lever engaging said reversing mechanism rack is longer than the 110 other arm of the lever, and the throw of said crank is less than the length of said long arm and greater than the length of said short arm of the lever.

4. In combination, a reciprocating bed, means for imparting forward and backward strokes at uniform speeds to said bed and idling with respect to the bed during each reversal of the direction of movement thereof, means for engaging and reversing the 120 movement of said bed adjacent to the end of each stroke and idling with respect to the bed during the major portion of each stroke, a part of said bed means being in continuous driving connection with the bed and a part 125 of said bed driving means acting as a drive for the reversing means.

5. In combination, a reciprocating bed having a reverse rack at each end and a main driving rack, bed driving means having a 130

portion continually engaging said main rack, said means idling with respect to the bed during the reversing movements thereof, and means for engaging one of said reverse racks 5 and reversing the movement of the bed adjacent to the end of each stroke and idling with respect to the bed during the main driving thereof.

6. In combination, a reciprocable bed having a reverse rack at each end, means for driving said bed and idling with respect thereto at the reversing points in its movements, and a reversing mechanism having a reciprocably movable member and an element for connecting said member with one or the other of said bed reverse racks to communicate a reversing movement to the bed at the end of each stroke, the movements of said member during a bed reversing 10 period being reverse to the movements of the bed whereby the reversing mechanism has a counter-balancing action to the bed during a reversing thereof.

7. In combination, a reciprocable bed having a reversing rack at each end, means for driving said bed and idling with respect thereto at the reversing points in its movements, and a reversing mechanism embodying a rack, means for reciprocating the rack, 25 and a lever having at one end a segment in mesh with said last rack and at its other end a segment which meshes with one or the other of said bed reverse racks to communicate a reversing movement to the bed at the 30 end of each stroke thereof, the direction of movement of the mechanism rack being reverse to the movements of the bed during each reversing period.

8. In combination, a reciprocable member having a reverse rack at each end, means for driving said member and idling with respect thereto at the reversing points in its movement, and a reversing mechanism embodying a reciprocably movable rack and a lever having one end in engagement with and rocked by movements of said rack and having at its other end a gear segment which meshes with one or the other of said member reverse racks at the end of each member 45 stroke to reverse the movement of the member.

9. A combination as called for in claim 8, wherein the arms of said lever are of different lengths.

10. In combination, a reciprocable member, means for moving said member at uniform speed during part of both forward and backward strokes thereof, said means idling with respect to the member during each reversal of the direction of movement thereof; said means including a part in continued engagement with said member; means including a part for engaging and reversing the movement of said member at the end of 60 the uniform part of each stroke and idling

with respect to the member during the uniform portion of each stroke, the said means for moving the member uniformly and the said reversing means being disconnected; and a common means for driving both said member moving means and said member reversing means, substantially as described. 70

11. In combination, a reciprocable member, a primary driving means; a rotatable means continuously driven at uniform speed by said driving means; member moving means periodically connecting with said rotatable means to operate in unison therewith and when so connected imparting a uniform movement to said member during the forward and backward stroke thereof; and reversing means for connecting said primary driving means and said member at the end of the uniform part of each stroke of said member to reverse the movement of said member; 80 the connection between said member moving means and the primary driving means being disconnected during the reversing movements of the member; and the connection between said reversing means and said member being disconnected during the uniform parts of the stroke of said member substantially as described. 90

12. In combination, a reciprocable member, reverse racks at opposite end portions of 95 said member, a main drive means, means driven by said main drive means and operable to engage one or the other of said racks at predetermined points in a movement of the member and to impart a reversing movement thereto, a rotatable element continuously driven at uniform speed by said drive means, and mechanism automatically operable to connect said element and member and impart one stroke from the former to the 100 latter and to connect said main drive means and member to impart the return stroke to the member. 105

13. In combination, a reciprocable member, a main drive means, means driven by 110 said main drive means and operable to engage said member at the end of each stroke and impart a reversing movement thereto, a rotatable element continuously driven in one direction by said drive means, and means 115 permanently connected with the member and operable to connect with and be driven by said element during one stroke of the member and to disconnect said element and connect with and be driven by said main drive means during the next stroke of the member. 120

14. In combination, a reciprocable member, a main drive means, reversing means driven by said main drive means and operable to engage said member at the end of each stroke and impart a reversing movement thereto, a rotatable element continuously driven in one direction by said drive means, means having permanent rack and 125 130

pinion connection with said member and operable to impart forward and backward strokes thereto, said last means being automatically operable to connect with said element and be driven thereby during one stroke of the member and to release said element and connect with and be driven by said main drive means during the return stroke of the member, said member driving means 10 being released from both said element and main drive means during the reversing movements of the member.

15. In combination, a reciprocable member, a main drive shaft, means driven by said shaft and operable to engage and impart a reversing movement to said member at the end of each stroke thereof, a rotatable element continuously driven by said shaft, mechanism having a rotatable shaft in rack 20 and pinion connection with said member and operable to connect with and be driven by said element during one stroke of said member and to release said element and be driven by said main drive shaft during the return 25 stroke of said member, said mechanism idling with respect to both said element and main shaft during each reversing movement of said member.

16. In combination, a reciprocable member, a main drive means, reversing means continuously driven by said main drive means and operable to engage and reverse the movement of said member at the end of each stroke thereof, a rotatable element continuously driven at uniform speed by said drive means, a driven shaft, rack and pinion connection between said shaft and member, and mechanism automatically operable to connect said shaft and element during one 40 stroke of said member and to release said element and connect said shaft and main drive means to drive the shaft in a reverse direction and impart a return stroke to said member, said mechanism having a part which is 45 released from both said element and main drive means during each reversing movement of the member to permit an idling of said shaft.

17. In combination, a reciprocable member, a main drive means, means driven by said main drive means and operable to engage and reverse the movement of the member at the end of each stroke thereof, a rotatable element continuously driven by said 55 drive means, a driven shaft, rack and pinion connection between said shaft and member, a gap-gear fixed to said shaft and automatically operable to connect said element and gear to drive said shaft during one stroke of 60 the member and to disconnect said element and gear and connect the main drive means and gear to impart the return stroke to said member, said mechanism operating in the gear gap during each reversing movement of

said member, whereby said shaft idles during 65 such reversing movements.

18. In combination, a reciprocable member, a main drive shaft, reversing means driven by said shaft and operable to engage and impart a reversing movement to said member at the end of each stroke thereof, a driven shaft, connection between said driven shaft and member for imparting reciprocation to one from a rotation of the other, a rotatable element continuously driven by 75 said main shaft, and normally loose with respect to said driven shaft, a gap-gear fixed to said driven shaft, and means embodying a plurality of gears which are driven by said main shaft and automatically operable to 80 connect and impart rotation to the gap-gear from said element during one stroke of the member and to connect said main shaft and gap-gear to drive the latter during the other stroke of the member, said driven shaft running idle during the reversing movements of 85 said member due to the gap in the gap-gear.

19. In combination, a reciprocating bed and a main driving means therefor embodying a driven shaft, continuous rack and pinion connection between said bed and shaft, a loose gear and a fixed gap-gear on said shaft, a drive shaft continuously rotating in one direction, a direct drive pinion and a main reverse pinion fixed to said drive shaft with 90 the former in constant mesh with said loose gear, a coupling pinion and a secondary reverse pinion mounted at one side of said drive shaft for rotary and axial shifting movements, said coupling pinion being in 95 constant mesh with said loose gear and shiftable into and out of coupling connection with both said loose and gap-gears, and said secondary reverse pinion being in constant driving connection with said main reverse 100 pinion and shiftable into meshing register with said gap-gear when the coupling pinion is shifted from register therewith, and vice versa; means for periodically shifting said axially movable pinions in one direction at 110 one revolution of the gap-gear and in the opposite direction at the succeeding revolution thereof when its gap is in register therewith, and means for reversing the direction of movement of the bed during the shifting period of said axially movable pinions. 115

20. A combination as called for in claim 19, together with means for continuously driving said reversing means from said drive shaft. 120

21. In combination, a reciprocating bed; a rack connected therewith; a gear meshing said rack; an oscillatory shaft carrying said gear; means for driving said shaft in one direction during the forward stroke of the 125 bed; means for driving said shaft in the opposite direction during the return stroke of the bed; said driving means disengaging

the shaft during the reversals of the bed; with means for reversing the bed at the ends of its strokes and while the shaft driving means is disconnected therefrom, said means 5 operating through the said bed rack and gears to control the movements of the oscillatory shaft during the reversals of the bed.

22. In combination, a reciprocating bed; a rack connected therewith; a gear meshing 10 said rack; an oscillatory shaft carrying said gear; a gap gear on the said shaft; oppositely rotatable driven gears adapted to be alternately engaged with the said gap gear to drive the latter and the shaft in opposite 15 directions; both said gears being disengaged from the gap gear during the period of reversals of the bed; with means for reversing the bed at the ends of its strokes and while the said driven gears are disengaged from 20 the gap gear; said reversing means operating through the said rack and gear to control the movements of the said shaft and gap gear during the reversals of the bed.

23. In combination, a reciprocating bed; 25 a pair of racks connected therewith at opposite sides of the longitudinal center of the bed; a pair of gears meshing said racks; an oscillatory shaft carrying said gears; means for rotating said shaft in one direction during the forward stroke of the bed; means for driving said shaft in the opposite direction during the return stroke of the bed; said driving means disengaging the shaft 30 during the reversals of the bed with means for reversing the bed at the ends of its strokes and while the shaft driving means is disconnected therefrom, said means operating through the racks and gears to control the movements of the oscillatory shaft 35 during the reversals of the bed.

24. In combination, a reciprocating bed; a pair of racks connected therewith at opposite sides of the longitudinal center of the bed; a pair of gears meshing said racks; an oscillatory shaft carrying said gears; a gap 40 gear on the said shaft; oppositely rotatable driven gears adapted to be alternately engaged with the said gap gear to drive the latter and the shaft in opposite directions; both said gears being disengaged from the gap gear during the period of its reversal; with means for reversing the bed at the ends of its strokes and while the said driven gears are disconnected from the gap gear, said 45 reversing means operating through the said racks and gears to control the movements of the said shaft and gap gear during the reversals of the bed.

25. In combination, a reciprocating bed; 50 a rack connected therewith; a gear meshing said rack; an oscillatory shaft carrying said gear; means for rotating said shaft in one direction during the forward stroke of the bed; and means for driving said shaft 55 in the opposite direction during the return

stroke of the bed; said means disengaging the shaft during the reversal movements of the bed; with means for reversing the bed at the ends of its strokes, comprising a reverse rack at each end of the bed; a reciprocatory rack bar; a toothed member engaged with said rack and having a portion adapted to alternately mesh with one or the other of the reverse racks at the end of a stroke of the bed; and means for actuating 70 said rack to cause the reverse means to take control of and reverse the bed while the said shaft driving means is disengaged therefrom; the said bed rack and gear remaining constantly in mesh and serving 75 while the reversing mechanism controls the bed to reverse the direction of rotation of the said shaft and bring it up to the proper speed, substantially as described.

26. In combination, a reciprocating bed; a rack connected therewith; a gear meshing said rack; an oscillatory shaft carrying said gear; a gap gear on the said shaft; oppositely rotatably driven gears adapted to be alternately engaged with the said gap gear 90 to drive the latter and the shaft in opposite directions, both said gears being disengaged from the gap gear during the period of reversal; with means for reversing the bed at the ends of its strokes, comprising a reverse rack at each end of the bed; a reciprocatory rack bar, a toothed member engaged with said bar and having a portion adapted to alternately mesh with one or the other of the reverse racks at the end of a stroke of the bed; and means for actuating 95 said rack to cause the reverse means to take control of and reverse the bed while the said driven gears are disconnected from the gap gear; the said bed rack and gear remaining constantly in mesh and serving while the reversing mechanism controls the bed to reverse the direction of rotation of the said shaft and gap gear and bring it up to speed, substantially as described.

27. In combination, a reciprocating bed; a pair of racks connected therewith at opposite sides of the longitudinal center of the bed; a pair of gears meshing said racks; an oscillatory shaft carrying said gears; means for rotating said shaft in one direction during the forward stroke of the bed; and means for driving said shaft in the opposite direction during the return stroke of the bed; said means disengaging the shaft 115 during the reversal movements of the bed; with means for reversing the bed at the ends of its strokes comprising a reverse rack at each end of the bed; a reciprocatory rack bar, a toothed member engaged with said rack bar and having a portion adapted to alternately mesh with one or the other of the reverse racks at the end of a stroke of the bed; and means for actuating said rack bar to cause the reverse means to take control 120 of and reverse the bed while the said driven gears are disconnected from the gap gear; the said bed rack and gear remaining constantly in mesh and serving while the reversing mechanism controls the bed to reverse the direction of rotation of the said shaft and gap gear and bring it up to speed, substantially as described.

125

- trol of and reverse the bed while the said shaft driving means are disengaged therefrom; the said bed racks and gears remaining constantly in mesh and serving while the reversing mechanism controls the bed to reverse the direction of rotation of the said shaft and bring it up to the proper speed, substantially as described.
28. In combination, a reciprocating bed; 10 a pair of racks connected therewith at opposite sides of the longitudinal center of the bed; a pair of gears meshing said racks; an oscillatory shaft carrying said gears; a gap gear on the said shaft; oppositely rotatably 15 driven gears adapted to be alternately engaged with the said gap gear to drive the latter and the shaft in opposite directions, both said gears being disengaged from the shaft during the period of its reversal; with 20 means for reversing the bed at the ends of its strokes comprising a reverse rack at each end of the bed; a reciprocatory rack bar, a toothed member engaged with said rack bar and having a portion adapted to alternately 25 mesh with one or the other of the reverse racks at the end of a stroke of the bed, and means for actuating said rack to cause the reverse means to take control of and reverse the bed while the said shaft driving means 30 is disengaged therefrom, the said bed racks and gears remaining constantly in mesh and serving while the reversing mechanism controls the bed to reverse the direction of rotation of the said shaft and gap gear 35 and bring it up to proper speed, substantially as described.

29. In combination, a reciprocatory slide having a slot, a crank pin engaging said

slot to reciprocate the slide; pinions on said slide adjacent opposite ends of the slot; and 40 fixed racks engaging said pinions, to prevent twisting or tilting of the slide by the lateral pressure of the crank pin thereon.

30. In combination, a reciprocating rack bar; a slide connected therewith having a 45 slot, a rotatable member having a crank pin engaging said slot to reciprocate the slide; a shaft mounted on said slide parallel with the slot; pinions on said shaft adjacent opposite ends of the slot, and fixed rack bars 50 meshing with said pinions, whereby twisting or tilting of the slide due to the lateral pressure of the crank pin thereon is prevented.

31. In combination, a reciprocable member, means for moving said member at uniform speed during part of both forward and backward strokes thereof and idling with respect to the member during each reversal of the direction of movement thereof; said means including an oscillating part in continual engagement with said member; means including an oscillating lever for engaging and reversing the movement of said member at the end of the uniform part of 60 each stroke and idling with respect to the member during the uniform portion of each stroke, the said means for moving the member uniformly and the said reversing means being independent; and a common means 65 for driving both said member moving means and said member reversing means, substantially as described.

In testimony whereof, I have hereunto signed my name to this specification.

MICHAEL A. DROITCOUR.
